(57) **CLAIM**

The ornamental design for an ear implant, as shown and described.

DESCRIPTION

FIG. 1 is a front view of the ear implant, with the base of the ear implant for implantation.

FIG. 2 is a rear view of the ear implant of FIG. 1.

FIG. 3 is an isometric view of the ear implant of FIG. 1, showing the ear shape that is visible upon implantation.

FIG. 4 is an isometric perspective view of the ear implant of FIG. 1, with the implant tilted slightly to the left direction of the page.

FIG. 5 is a posterior view of the ear implant of FIG. 1.

FIG. 6 is an inferior view of the ear implant of FIG. 1.

FIG. 7 is a superior view of the ear implant of FIG. 1.

FIG. 8 is a posterior perspective view of the ear implant of FIG. 1, rotated with respect to the angle of FIG. 5; and, FIG. 9 is another front perspective view thereof.

The base of the ear implant is visible to the surgeon when the implant is provided to the surgeon. The surgeon can shape the base if desired, prior to implantation.

The evenly dotted broken lines in the drawings illustrate unclaimed features of the ear implant and form no part of the claimed design. The lines contour lines are added for dimension only and form no part of the claimed design.

1 Claim, 9 Drawing Sheets
